United States Patent Office.

JEROME WHEELOCK, OF WORCESTER, MASSACHUSETTS.

Letters Patent No. 64,052, dated April 23, 1867.

IMPROVEMENT IN STEAM-ENGINE PISTONS.

The Schedule referred to in these Letters Patent and making part of the same.

TO ALL WHOM IT MAY CONCERN:

Be it known that I, JEROME WHEELOCK, of Worcester, in the county of Worcester, and State of Massachusetts, have invented a new and improved Piston for Steam Engines; and I do hereby declare that the following is a full, clear, and exact description thereof, which will enable others skilled in the art to make and use the same, reference being had to the accompanying drawings, which make a part of this specification, in which—

Figure 1 represents a side elevation of the piston.

Figure 2 is a central axial section of the same.

Figure 3 is a plan or face view.

Figure 4 is the same view with the piston-rod removed.

Similar letters of reference indicate corresponding parts in all the figures.

This invention relates to that class of pistons which are made solid or without a movable follower, and are provided with annular grooves for the purpose of receiving segmental or other packing rings, which fit into said grooves, and are set out and held out against the inner surface of the cylinder by the action of steam or suitable springs provided for that purpose. The invention consists in combining with a piston, which is cast or made hollow, stay-bolts or braces, which pass through and are secured to and mutually support each of the plates of the piston-head; it consists further in constructing the centre hole, through which the piston-rod passes, of such a shape that, when the piston is used in a horizontal engine, the piston-rod can be adjusted and kept at all times in the centre of the cylinder; it also consists in making a slot in the end of the piston-rod which is secured to the piston-head for the purpose hereinafter more fully explained.

A represents a metallic piston-head, which is fitted loosely to the bore of the engine cylinder. This head is provided with annular grooves on the periphery, into which are fitted suitable packing rings which operate in a manner to prevent the escape of steam before having done its work. B is a piston-rod, one end of which passes through the hole C in the piston-head A, and is secured thereto by the nut D. E E E are stay-bolts or braces which pass through each of the plates of the piston-head and are provided with screw-threads on each end which correspond with and fit into threads cut in said plates. These braces are intended to support the plates but do not draw them together, as the "lead" of the screw on each end of the bolts is the same. It being necessary for the bolts to pass entirely through from one plate to the other, that part of the bolt which is in the interior of the piston is reduced so as to pass through the holes freely. When the bolts are screwed into place, the ends which project slightly through the plates are riveted over, thus making a steam-tight joint and preventing them from casually turning from their places. It will be seen that these bolts perform the double purpose of bracing the piston and stopping the holes which must necessarily be left in the plates that the core or interior part of the mould may be removed from the casting. The end of the rod which passes through the piston-head is provided with a collar, situated at a proper distance from the end, which forms a suitable abutment for one side or face of the piston, which is pressed up against said collar and held firm by the nut D on the opposite side. The hole G is made of an oblong shape, or, in other words, it is made larger up and down so that the piston-rod may be adjusted, as the piston wears, from the centre line of the cylinder by suitable chips placed in the space between the rod and lower surface of the hole. As the piston is not liable to wear on the sides, the rod can be made to nearly fill the hole horizontally, so that when said rod is in proper position up and down it is sure to be in the centre of the cylinder. As the nut D may remain a long time in position without being removed and thereby liable to stick or become rigid on the rod, I make a slot in the end of the rod over which the nut D is screwed. The object of this slot is that when the nut becomes fast on the rod and an extra strain is necessary to start said nut, the end of the rod will become compressed and allow the nut to unscrew. In cases where this arrangement is used with steam from bad or salt water and the slot liable to become filled up or corroded, a "cap-nut" or other suitable covering may be used to cover the end of the rod, but in ordinary cases it will not be found necessary.

I have shown my piston with a recess on each side, for the purpose of receiving the collar on the one side and the nut on the opposite side, but when the cylinder is of sufficient length the collar and nut may draw up against the outside of the plates. By this arrangement a piston is obtained which is extremely light, is constructed of few parts, and at the least possible expense, and is very strong and durable.

I claim as new, and desire to secure by Letters Patent—

1. The combination of stay-bolts E E E with a piston-head, substantially in the manner herein described.
2. A piston constructed with an oblong hole or aperture through its centre to receive the piston-rod, substantially as and for the purpose described.
3. The slot in the piston-rod B, when used for the purpose of relieving the nut, in the manner substantially as shown and described.

JEROME WHEELOCK.
